EXEMPLARY CLAIM

1. Apparatus for maintaining an underwater device at a substantially predetermined depth in water, comprising; gas release means including a valve body, a valve seat movable relative to the valve body, a balloon attached to the valve body and to said device, an umbrella attached to the valve seat adapted to move same relative to the valve body in accordance with velocity of the apparatus in a generally vertical direction, means for generating gas within the balloon, said gas release means communicating with the inside of the balloon, a valve cooperating with the valve seat, hydrostatic pressure responsive means for moving said valve relative to the valve body and valve seat in accordance with hydrostatic pressure, the construction and arrangement being such that the amount of gas released from the balloon by the gas release means is a function of said velocity and pressure.

1
DEPTH CONTROL

This invention pertains generally to apparatus for maintaining a device under water at a fixed depth. More particularly it relates to a depth control for maintaining an expendable underwater device at a fixed depth for a predetermined time.

In naval tactics several potent weapons have been designed with a view to detecting and attacking submarines. Some of these weapons depend for their efficacy on the noise produced and emitted by the submarines. As a defensive measure in aid of the submarine, it has been proposed to utilize a device that may be dropped by aircraft, surface vessels, and submarines, and that will produce sound for the purpose of confusing the attacker. The advantages of such a decoy will be obvious.

In order to simulate the sound of a submarine and to effectively serve as a decoy, it is necessary that the noisemaker operate at a predetermined depth. For example, in a preferred form of noisemaker, which is adapted to be ejected from a submarine from depths as great as 400 feet, the device rises to its operating depth of 40 feet and is designed to remain at that depth for 10 to 12 minutes, during which time it emits its noise; thereafter, the assembly sinks to the bottom and leaves no trace.

In general, the decoy or noisemaker may comprise an explosive stack in the form of a cylinder. Detonation of the explosive elements will generate the desired signals. The upper portion of this cylinder is attached to the lower portion of another cylinder that contains the depth control device for propelling the noisemaker to a predetermined depth and for maintaining that depth.

The depth control device comprises a strong airtight fabric balloon. At the proper time this balloon is subjected to the action of the seawater that enters through apertures made for that purpose. Within the depth control cylinder is a chemical that is designed to react with water to generate a buoyant gas. In a preferred form of the invention this gas is hydrogen. The device is so designed that sufficient hydrogen is generated to impart positive buoyancy to the decoy or noisemaker to bring the noisemaker to a desired depth under water and to maintain that depth for a predetermined time. During this interval of equilibrium, the noisemaker will operate to send out the desired signals, and at the completion of its mission the whole device will sink to the bottom of the sea.

The invention will be more clearly understood with the aid of the accompanying drawings.

In these drawings:

FIG. 1 is an elevation of the complete device comprising the depth control and the noisemaker;

FIG. 2 is an elevation of the device during knock-off, that is, during the process when the balloon is emerging from its container;

FIG. 3 is an elevation of the balloon just after knock-off;

FIG. 4 is a schematic view of the depth control device in its equilibrium position;

FIG. 5 is an enlarged view, partially in section, of the depth control device;

FIG. 6 is an elevation, partially in section, of the gas release valve.

The elements constituting the depth control are enclosed in a rigid sealed metallic container 10. The signal generator or noisemaker is enclosed in a cylindrical

2

stack 11. The upper part of the stack 11 is secured to the bottom of the container 10.

Within the container 10 and bearing against the inner wall thereof are two cylindrical half shells 13 and 14.

5 These half shells 13 and 14 when assembled together form a complete open-ended cylinder. They are not attached to each other or to the container 10 but are held in their position against the inner wall of the container 10 by a flat spring 15 at the lower end of the half shells 13 and 14.

In the space within the half shells 13 and 14 are normally positioned a collapsed balloon 16 and a collapsed supporting umbrella 17. For the purpose of this invention it has been found that a material made of neoprene-impregnated Nylon fabric is eminently suitable for the balloon 16 and the umbrella 17. A large proportion of the space within the balloon 16 is filled with a mass 21 of ground calcium hydride. It is a property of this compound that when it mixes with water it reacts rapidly to form calcium hydroxide and hydrogen gas, in accordance with the following equation:

25 Within the balloon 16, there is, in addition to the ground calcium hydride 21, a stick 29 of the same chemical, calcium hydride, in solid form. This stick 29 is positioned longitudinally of the device within the balloon 16.

30 The Nylon fabric of the balloon 16 is provided with several apertures 34, and at the proper time, when the balloon is subjected to the action of the seawater, sufficient hydrogen will be evolved from the ground calcium hydride 21 to give a buoyant effect to the balloon and its cooperating structure. Due to its large effective surface, the ground calcium hydride 21 will rapidly generate a relatively large quantity of hydrogen gas. At the same time this ground calcium hydride 21 will of course be consumed rapidly. It is desired to obtain a 35 greater buoyant effect initially so as to arrest the falling of the device toward the bottom of the sea subsequent to its launching. While the water is reacting with the ground calcium hydride 21, it is also reacting with a portion of the stick 29, but because of its smaller surface compared to its volume, the stick 29 will not generate hydrogen gas as rapidly as the ground compound 21. By the time the ground calcium hydride 21 has been consumed, sufficient hydrogen is coming from the stick 29 to give the complete structure sufficient buoyancy at the predetermined depth to neutralize its gravitational effect and to maintain the entire assembly in equilibrium.

40 The equilibrium effect is obtained by means of a valve 22 positioned between the balloon 16 and the umbrella 17. This valve 22 is so designed that it releases the generated hydrogen gas at a rate just sufficient to maintain the device at its operating depth, for example, 40 feet below the surface, and the total quantity of calcium hydride is sufficient to maintain the depth for 10 to 12 minutes, during which time the signal generator emits its signal. Thereafter, the assembly sinks to the bottom of the sea and leaves no trace.

45 The stack 11 contains a noisemaker 23, and the noisemaker 23 is attached to the balloon 16 by a rope or wire 24 of the proper length. This length is sufficient to insure safety to the balloon 16 and the noisemaker 23 during the process of knock-off.

A fuze 26 leads from the center hole of the explosive stack 11 to a smokeless powder charge 27 at the top of the metal container 10. In order to prevent burning of the balloon 16 by the fuze 26, the latter is inclosed in a flexible, varnish-impregnated Fiberglass tube 28.

When the assembled structure is discharged from a submarine, a trigger device on the submarine actuates an igniter to ignite the fuze 26. When the charge 27 explodes, the container 10 is shot away, and the half-shells 13 and 14 are forced apart by the spring 15. Water entering the balloon 16 through the apertures 34 will react with the ground calcium hydride 21, rapidly filling the balloon 16 with hydrogen and making the system positively buoyant.

At the same time, the weight of the explosive stack 11 pulls downwardly on the bottom of the balloon 16 so that the balloon 16 turns topside up. The presence of the hydrogen gas making the balloon 16 positively buoyant, the depth control will rise. As it approaches the preset operating depth, usually 40 feet, the valve 22 will begin to release the gas until the operating position and neutral buoyancy are reached. During this time the stick 29 of calcium hydride reacts with the water to generate hydrogen continuously at a slow rate. The gas will be released just fast enough through the valve 22 to maintain stability and depth. If the device gets above its preset operating depth, the excess gas will be released and the device will fall to its equilibrium position. After ten to twelve minutes of constant-depth operation, the hydride stick 29 will be consumed and the device will fall to the bottom.

If the valve 22 did not release hydrogen at the proper time, the balloon 16 would be inherently unstable, for if the depth control device started to rise, the entrapped gas would become more buoyant and the device would rise still faster. Similarly, if the device should start to fall, the gas would become less buoyant and the device would fall continuously faster. Because a buoyancy-operated system is inherently unstable, the control system must supply a series of corrections, that is, it must reduce the net buoyancy to negative after it has become positive, then increase it to positive after it has become negative. The simplest mechanism for accomplishing this is to combine with the gas container a pressure-operated or depth-operated gas release valve and a continuous or controllable gas source. For such a system, the net force is equal to the net instantaneous buoyancy, and the resistance to motion is proportional to the velocity or some higher power of the velocity. The valve 22 is such that the velocity-operated component of control is combined with the pressure-operated component. Depending upon the relative sensitivities, the pressure component can be considered as a correction term to keep the slow drift to zero, or the velocity component can be considered a correction term to keep the hunting to a minimum. Appropriate sensitivity ranges for these two components exist that reduce both the drift and the oscillations to negligible values.

The gas utilized for imparting positive buoyancy to the depth control device may be obtained from the reaction of lithium metal, lithium hydride, or calcium hydride with sea water, to generate hydrogen. If desired, another source may be used, such as compressed nitrogen or liquified carbon dioxide. The preferred source, for the size and weight of signal generator contemplated in this application, is calcium hydride.

To avoid the passage of the finely ground calcium hydride 21 into the valve 22, a felt plug 31 is positioned at the bottom of the inlet of the valve 22. A cord 32 connects the valve plug 31 with the signal supporting means 24. The cord 32 is of such a length that the plug 31 is removed from the valve 22 by the load 23 as the balloon 16 is stretched after knockoff. The support 24 may be in the form of a coil spring that is initially positioned at the bottom of the container 10. The use of such a spring will permit the exertion of a downward force on the bottom of the depth control device immediately after knockoff while at the same time reducing to a minimum the possibility of damage due to the sudden shock. The spring 24 is a constant such that the weight of the sound device hanging from it stretches it out to a sufficient length so as not to impair the sound output from the signal generator.

The holes 34 in the lower portion of the balloon 16 serve two functions. One is to allow the entrance of sea water to react with the calcium hydride, and the second is to permit the escape of excess gas and hydride mixture. Because of the rapid filling of the balloon 16 with the hydrogen gas from the mass 21, the gas must be released, during ascent, at a rate much greater than can be taken care of by the valve 22. This excess gas is released through the holes 34 in the balloon 16.

As the depth control approaches or attains steady state operation, gas will also be released through a plurality of holes 36 at the top of the umbrella 17, at a rate just fast enough to offset the generation of gas by the stick 29 of calcium hydride. The net buoyancy of the balloon 16 plus its attached load 23 is thus kept substantially zero, and the depth is kept constant.

The umbrella 17 serves the double purpose of damping vertical motion and of actuating the velocity component of the valve action. It is designed to provide a maximum of damping resistance in a minimum of storage volume. The balloon 16 is large enough to float the load 23 and at the same time retain enough water for the hydrogen generation. During the rise to equilibrium depth, the water level in the balloon 16 is determined by the location of the holes 34 in the bottom of the balloon 16, and this water level is kept below the top of the calcium hydride stick 29. During steady state operation, the water within the balloon 16 rises to cover the stick 29.

The valve 22 will now be described in detail, with particular reference to FIG. 6.

The lower portion of the valve comprises an inlet tube 41. The felt plug 31 has a reduced portion that is adapted to fit within the opening of the inlet tube 41. The cord 32 extends through the plug 31 and it fastens to the top thereof by means of a ring 42. An inlet screen 43 positioned in the inlet tube 41 above the felt plug 31 aids in preventing ingress of the ground calcium hydride 21. A plurality of inlets 44 are thereby kept free for passage of the gas. After the gas passes upwardly through the inlets 44, it flows along the outside of a Sylphon bellows 45 and out between a valve ball 46 and its seat 57. Thence, the gas finds its way out of the depth control device through the holes 36.

The pressure component of control of gas release is supplied through the Sylphon bellows 45 and the position of the valve ball 46. The Sylphon 45 is pressure sealed at top and bottom and its stiffness is such that it shortens, for example, approximately 0.009 inches per lb. per sq. in. increase in pressure or 0.004 inches per

ft. increase in depth of the device. The Sylphon assembly 45 is screwed into the valve body 47 by means of a reduced portion 48 extending from the bellows 45. The position of the reduced portion 48 of the Sylphon 45 in the valve body 47 determines the operating depth. Consequently, adjustment of the reduced portion 48 provides a method of controlling the operating depth.

The velocity component of control of gas release is supplied through the longitudinal motion of the valve seat 57. The valve seat 57 can travel, for example 0.1 inches and is normally held at the center of this travel by two ring springs 49. The umbrella 17 is attached to the valve seat 57 and the top of the umbrella 17 is held between two grooves 51 in the outside of the seat 57 by means of two wire retaining rings 52. The spring constant of the centering springs 49 is about 0.35 inches per kilogram, and the restoring force is approximately linear for forces up to about 0.15 kilograms, or for valve seat travel of about 0.04 inches. A force of 0.15 kilograms on the umbrella 17 corresponds to a velocity of about 0.2 ft. per second. As a result, an upward velocity of about 0.2 ft. per second at the equilibrium position of the depth control device will open the valve 22 as much as the displacement upwardly of 10 feet from the equilibrium position. The velocity component of control begins to be effective as soon as the device gets to within 10 feet of its equilibrium position.

A preferred form of the invention is designed to be operated from a submarine. When the complete device is ejected from the vessel the knock-off fuze 26 is ignited by the flash from a heat transfer plug at the trigger end of the explosive stack 11. This heat transfer plug may incorporate a 5-second delay. The fuze 26 itself may have a period of 3 seconds before knock-off, so that there is an approximate 8-second delay between triggering and knock-off. If ejected from a depth of about 400 ft., the free fall of the device will be approximately 75 ft. additional, and the time of fall will be about 10 or 11 seconds. After knock-off the water will react with the ground calcium hydride 21 to generate a large amount of hydrogen very rapidly. This will give the device positive buoyancy so that it will begin to rise. This rise must begin to take place before the device has reached an arbitrary depth of, say, 600 ft. as the maximum desirable depth. The hydrogen generated from the ground calcium hydride 21 is much greater than can be taken care of by the valve 22 and the excess is released through the holes 34. The stick 29 produces a steady gassing rate at the proper time, and the depth control device obtains an equilibrium position, either by motion in one direction from its maximum depth, or by a series of damped oscillations that are a result of the release of gas from the valve in accordance with the pressure component of control of gas release and the velocity component of control of gas release. The equilibrium position is designed to be about 40 ft., and the time of operation of the signal generator to be about 10 to 12 seconds. At the conclusion of this period, all the calcium hydride has been consumed and the whole de-

vice will at once plummet to the bottom of the sea.

We claim:

1. Apparatus for maintaining an underwater device at a substantially predetermined depth in water, comprising: gas release means including a valve body, a valve seat movable relative to the valve body, a balloon attached to the valve body and to said device, an umbrella attached to the valve seat adapted to move same relative to the valve body in accordance with velocity of the apparatus in a generally vertical direction, means for generating gas within the balloon, said gas release means communicating with the inside of the balloon, a valve cooperating with the valve seat, hydrostatic pressure responsive means for moving said valve relative to the valve body and valve seat in accordance with hydrostatic pressure, the construction and arrangement being such that the amount of gas released from the balloon by the gas release means is a function of said velocity and pressure.

2. Apparatus in accordance with claim 1 wherein said pressure responsive means includes a bellows secured at one end to the valve body, its other end carrying the valve.

3. Apparatus in accordance with claim 2 wherein said bellows is adjustably secured to the valve body to permit adjustment of said predetermined depth.

4. Apparatus comprising a pair of axially aligned members releasably secured together in tandem relationship and adapted to be launched into water through a submarine torpedo tube, one of said members being a container adapted to be blown apart to expose its contents to the water and the other member being an underwater device, a flexible collapsed balloon disposed in said container, an umbrella within the container attached to the balloon, means connecting the balloon and said other member for suspending the latter from the former after said container is blown apart, means for blowing the container apart and releasing its contents after the apparatus has been launched, chemical means within the balloon adapted to react with water and form a buoyant gas within the balloon, and valve means for releasing gas from the balloon constructed and arranged to maintain the apparatus at a substantially predetermined depth in water, said umbrella adapted to damp movement of the apparatus in a generally vertical direction when it reaches its equilibrium depth of submergence.

5. Apparatus in accordance with claim 4 wherein said umbrella is connected to said valve means for operating same in accordance with velocity of the apparatus in said vertical direction.

6. Apparatus in accordance with claim 4 wherein said chemical means comprises a mass of particles adapted to rapidly form gas at a rate sufficient to maintain positive buoyancy, whereby the apparatus relatively rapidly rises to its equilibrium depth, and another mass adapted to form gas at a slower rate for maintaining the apparatus at the equilibrium depth.
